UNITED STATES PATENT OFFICE.

OTTO F. LUDWIG, OF ZILLAH, WASHINGTON.

PISTOL HOLSTER.

Application filed April 13, 1922. Serial No. 552,140.

To all whom it may concern:

Be it known that I, OTTO F. LUDWIG, a citizen of the United States, residing at Zillah, in the county of Yakima and State of Washington, have invented certain new and useful Improvements in Pistol Holsters; and I do hereby declare the following to be a full, clear, and exact description of the invention, such as will enable others skilled in the art to which it appertains to make and use the same.

The present invention relates to improvements in pistol holsters and has for an object to provide a device for holding a pistol or revolver in a concealed position along the forearm and to enable the pistol to be projected instantly into the hand ready for use.

It is another object of the invention to provide an improved pistol holster in which the parts will be simple and effective in action while compact to enable the weapon to be carried within the coat sleeve without exciting suspicion of its presence there.

A further object of the invention is to provide a compact and durable device in which the pistol may be released by the movement of the forearm against the body causing its forcible projection along the forearm and directly into the hand of the user.

With the foregoing and other objects in view, the invention will be more fully described hereinafter, and will be more particularly pointed out in the claims appended hereto.

In the drawings, wherein like symbols refer to like or corresponding parts throughout the several views,

40 Fig. 1 is a perspective view of the improved holster shown applied in position;

Fig. 2 is a side elevation thereof;

Fig. 3 is a cross section taken on the line 3—3 in Fig. 2;

45 Fig. 4 is a longitudinal section;

Fig. 5 is a horizontal section taken on the line 5—5 in Fig. 4;

Fig. 6 is a rear elevation; and,

50 Fig. 7 is an enlarged fragmentary detail with parts broken away and parts in section.

Referring more particularly to the drawings, the device comprises a casing composed of side walls 1 and 2, a bottom wall 3 and a top 4 which may be made of sheet metal or like material. The inner wall 2 is provided

with upper and lower flanges 5 and 6 adapted to embrace the forearm of the user as indicated in Fig. 1 and to be held thereon by the use of straps 7 or the like, which are suitably connected to the flanges and provided with buckles 8 for adjustment.

The flanges and wall 2 will be shaped to fit the inner side of the forearm whereby the device may be carried between the forearm and the body. The pistol or revolver indicated at 9 is adapted to be received in the compartment furnished by the casing walls and preferably the revolver is provided laterally with a headed stud or pin 10 adapted to fit a slot 11 on the inner face of the wall 2 which may be made by pressing the sheet metal material outwardly.

Flanges 12 are adapted to overhang the slot 11 to confine the head of the pin and to guide the pistol in place. The pistol handle fits against an abutment 13 upon the rear end of a slide 14 which is adapted to move back and forth in a slot 15 made in the bottom 3 and guided therein by the upper and lower tongues 16 and 17 carried by the slide and fitting above and below the side walls of the slot 15. The slide is normally drawn outward by a coil spring 18 affixed at one end to a clip 19 secured beneath the forward end of the bottom 3 and to a similar clip 20 upon the inner end of the slide 14.

A catch 21 is adapted to engage with the forward edge of the pistol handle as indicated in Figs. 4 and 7, and is provided with a forward flared flange 22 to guide the catch outwardly when the pistol is being moved into the holster. The catch 21 is carried by an arm 23 of metal or other suitable material being pivoted at 24 in ears 25 extending from the inner wall 2 and having an offset tail piece 26 provided with a stud 27 for operation. A coil spring 28 is connected between the arm 23 and the wall 2 and yieldingly acts to draw the catch 21 into engagement with the pistol.

In the use of the device, the holster is strapped to the forearm in the position indicated in Fig. 1, and the pistol 9 is shoved into the forward open end handle first, the handle engaging the abutment 13 which is shaped to receive it and causing the slide 14 to move rearwardly as the pistol is pushed back into the case, care being taken to see to it that the headed stud or pin 10 engages in the slot 11 which will center the pistol

and prevent its handle from escaping from the catch 21 which engages a flat forward portion of the handle when the pistol assumes its final position in the holster as indicated in Fig. 4.

The device is thus carried about until the occasion arises for its use. It is concealed during all of this time within the sleeve of the wearer and by the simple expedient of 10 clamping the stud 27 against the side of the body, the catch 21 may be released and the spring 18 will quickly project the slide 14 and thrust the pistol into the hand, as illustrated in Fig. 1. The pistol in this case is 15 then ready for immediate use and it enables the weapon to be drawn quickly and projected directly into the hand. It will be found to be an excellent device for policemen, detectives, watchmen, and the like.

20 It is obvious that various changes and modifications may be made in the details of construction and design of the above specifically described embodiment of this invention without departing from the spirit thereof, such changes and modifications being restricted only by the scope of the following 25 claims.

What is claimed is:

1. A pistol holster comprising a casing 30 adapted to be carried upon the forearm and to receive a pistol therein, means for projecting the pistol from the casing into the hand; and yieldable means for normally holding said last named means from operation, substantially as described.

2. A pistol holster comprising a casing 35 adapted to be strapped to the forearm next the body and to slidably receive a pistol, means to project the pistol from the casing into the hand, and a trigger normally hold-

ing the pistol in the casing and adapted to be tripped against the body, substantially as described.

3. A pistol holster comprising a casing having means to secure it to the forearm, a 45 spring-pressed slide in the casing for projecting the pistol therefrom, and a trigger for holding the pistol and slide with the spring under tension, substantially as described.

50 4. A pistol holster comprising a casing adapted to receive a pistol, guide means carried by the pistol and casing, a slide having an abutment engaged by the pistol, spring means associated with the slide, and a releasable trigger for holding the slide and pistol at an inner position in the casing, substantially as described.

55 5. A pistol holster comprising a casing having a portion to lap about the forearm 60 with means to secure the same thereto, a slide in the casing adapted to receive a pistol, spring means for moving the slide in one direction to project the pistol, and a trigger mechanism for releasing the slide 65 and pistol, substantially as described.

6. A pistol holster comprising a casing 70 having a slot in one side with flanges overhanging the slot, a pistol receptacle in the casing having a headed pin to fit in said slot, a slide guided for movement in the casing and receiving the handle of the pistol, a spring to move the slide in one direction, and a spring-pressed pivoted trigger having 75 a catch with a beveled nose adapted to engage the handle and having an off-set portion projecting beyond the casing, substantially as described.

OTTO F. LUDWIG.
